UNITED STATES PATENT OFFICE.

CHARLES STASTKA, OF PITTSBURG, PENNSYLVANIA.

MANGLE.

No. 906,325.

Specification of Letters Patent.

Patented Dec. 8, 1908.

Application filed March 31, 1908. Serial No. 424,388.

To all whom it may concern:

Be it known that I, CHARLES STASTKA, a subject of the Emperor of Austria-Hungary, residing at Pittsburg, in the county of Allegheny and State of Pennsylvania, have invented certain new and useful Improvements in Mangles, of which the following is a specification, reference being had therein to the accompanying drawing.

10 This invention relates to mangles, and to certain new and useful improvements upon my mangle as disclosed in an application filed Feb. 13th, 1908, Serial No. 415,639.

In the present application, I have devised 15 novel vacuum cylinders to be used in lieu of the dash pots of my former invention and a simple reversing device for controlling the movement of the pin rack of my mangle.

These improvements will be presently described in detail and reference will now be had to the drawing forming a part of this specification, wherein,

Figure 1 is a longitudinal sectional view of my mangle, Fig. 2 is a plan of the same, 25 Fig. 3 is a front elevation of my reversing device, Fig. 4 is a side elevation of the same, Fig. 5 is an end view of the mangle, and Fig. 6 is a horizontal sectional view of a portion of the mangle taken on the line 30 $x-x$ of Fig. 1. Fig. 7 is a detail view, showing the exhaust valve mechanism.

In the accompanying drawings, I have illustrated my mangle or laundry machine as comprising a suitable bed 1 having side 35 frames 2. Between the side frames is arranged a reciprocating device comprising a box-like structure 3 adapted to bear directly upon the rolls 4 upon which the fabric or clothes are wound to be smoothed and 40 treated by the mangle. The box-like structure 3 is filled with suitable material (not shown) to add weight to the same, whereby when the device is reciprocated sufficient pressure will be exerted upon the rolls 4.

45 Upon each end of the box-like structure 3, I locate a guide 5 having an elevated inverted vacuum cylinder 6, said vacuum cylinders communicating by a pipe 7 with a valve 8, the casing of the latter adapted to 50 communicate with a vacuum pump (not shown), whereby said cylinders can be exhausted of air. Arranged in each vacuum cylinder is a piston head 9 having a depending piston rod 10 supporting a pin rack 11, 55 the ends of said rack being housed by the guides 5.

The side frames 2 intermediate their ends are provided with a transverse beam 12, providing bearings for a driven shaft 13. This shaft through the medium of gear wheels 14 drives a shaft 15, said shaft having a star wheel 16 adapted to mesh with pins 17 carried upon one side of the rack 11. The opposite side of the rack 11 adjacent to its ends is provided with pins 18 adapted to 60 engage a reversing device 19 arranged upon the beam 12. The reversing device 19 is cut away to provide two semi-circular paths 20 for the pins 18, also with a roller bearing 21 for the upper edge of the rack 11. 70

In operation, I will assume that a rotary movement is imparted to the shaft 13, and that through the medium of the gear wheels 14 the shaft 15 is driven. The star wheel 16 carried by said shaft will impart a reciprocating movement to the pin rack 11, and as this pin rack is connected to the box-like structure 3, said structure will be reciprocated upon the bed 1. Assuming that one 75 end of the pin rack 11 is reached, the pin 18 at that end of the rack will contact with the reversing device and will ride around upon the path 20 of the reversing device, also the pin rack, placing the pin 17 thereof in engagement with the under side of the star wheel 16. The pin rack will then be moved in the opposite direction until the other end of the pin rack is reached at which time the pin 18 at that end thereof contacts with the reversing device and starts the 80 rack in the opposite direction. During this movement of the pin rack, the same is maintained in a horizontal position by the piston heads 9 within the vacuum cylinders 6, but the box-like structure can be tilted whenever it is necessary to place a new roll of clothes under the reciprocating device. 85

The rollers 22 are provided for partially supporting the box like structure 3, during the movement of the latter. 90

Having now described my invention what I claim as new, is:—

1. In a mangle, the combination with a bed, and a plurality of rolls mounted upon said bed, of a box-like structure adapted to 105 be reciprocated upon said rolls, vacuum cylinders carried by said box-like structure, a pin rack, piston heads connected to said pin rack and adapted to move in said vacuum cylinders, a revoluble star wheel for 110 moving said pin rack, a reversing device supported above said bed and having semi-

circular paths, pins carried by said pin rack for engaging the paths of said reversing device for reversing the movement of said pin rack and said box-like structure.

5 2. In a mangle, the combination of a bed, a reciprocating device arranged on said bed, rolls interposed between said bed and said device, a pin rack for reciprocating said device, vacuum cylinders for cushioning said

pin rack, and a reversing device arranged 10 above said bed for imparting reverse movements to said pin rack.

In testimony whereof I affix my signature in the presence of two witnesses.

CHARLES STASTKA.
